UNITED STATES PATENT OFFICE

CLARA B. BICKEL, OF SAN FRANCISCO, CALIFORNIA

DESIGN FOR A NOVELTY DOG

Application filed May 23, 1931. Serial No. 39,950. Term of patent 3½ years.

To all whom it may concern:

Be it known that I, CLARA B. BICKEL, a citizen of the United States, residing at San Francisco, in the county of San Francisco and State of California, have invented a new, original, and ornamental Design for Novelty Dog, of which the following is a specification, reference being had to the accompanying one sheet of drawings, forming part thereof,

I claim:

The ornamental design for a novelty dog as shown.

CLARA B. BICKEL.
